UNITED STATES PATENT OFFICE.

ERASTUS E. WINKLEY, OF LYNN, MASSACHUSETTS, ASSIGNOR TO UNITED SHOE MACHINERY CORPORATION, OF PATERSON, NEW JERSEY, A CORPORATION OF NEW JERSEY.

PRESS FOR USE IN THE MANUFACTURE OF BOOTS AND SHOES.

Application filed March 19, 1919. Serial No. 283,609.

To all whom it may concern:

Be it known that I, ERASTUS E. WINKLEY, a citizen of the United States, residing at Lynn, in the county of Essex and State of Massachusetts, have invented certain new and useful Improvements in Presses for Use in the Manufacture of Boots and Shoes; and I do hereby declare the following to be a full, clear, and exact description of the invention, such as will enable others skilled in the art to which it appertains to make and use the same.

This invention relates to presses for use in the manufacture of boots and shoes, and it has particular reference to such presses as are employed for maintaining pressure while the paste is drying or setting, upon articles of superposed freshly pasted layers, such as built-up leather heel sections, veneered soles, pasted counters, boxes, etc.

One of the objects of the invention is to provide a press of the above indicated class, which shall be simple and inexpensive in construction; effective, reliable and expeditious in operation, and which shall be particularly adapted to subject the articles operated upon to individual and uniformly distributed pressures of predetermined amounts.

Another object of the invention is to provide a press of this general type which, without adjustments, shall be capable of operating upon a variety of classes of multi-layer articles of different shapes and forms.

Another object of the invention is to provide a press that shall be especially adapted to yieldingly conform to the configuration or contour of the laminated articles being pressed in such manner as to hold the edges of the component layers thereof under pressure so as to insure firm and close edge joints.

A further object of the invention is to provide a press that shall require a minimum amount of skill and attention during its operation, and more particularly a continuously operated press of such form that the articles to be pressed may be loaded into the press without the exercise of care respecting either the positions of the articles or the operating conditions of the press itself.

With these and other objects in view, the features of the invention comprises certain constructions, arrangements, and combinations of parts hereinafter described and claimed, the advantages of which will be obvious to those skilled in the art. 55

The several features of the invention will be readily understood from the following description and the accompanying drawings, 60 in which:—

Figure 1 is a side elevation of the machine, shown as operating upon a plurality of articles; and Fig. 2 is a plan view of the 65 machine.

The machine illustrated in the drawings is furnished with a main shaft 10 which extends through and is journaled in standards 12, secured to the base of the machine. 70 Said shaft 10 is driven by a worm wheel 14 secured thereto, which is connected through suitable speed reducing gearing to a worm 16 carried by a driving shaft 18. This driving shaft is journaled in the frame of the 75 machine and is provided with fast and loose belt pulleys 20.

The main shaft 10 carries a pulley 22 of relatively large diameter. A pair of belts 24 and 26 extend around the pulley 22 in 80 superposed relation. The inner belt 24 is guided and tightly held about the pulley 22 by a guide pulley 28. This guide pulley is spaced from the pulley 22 and is journaled on a shaft 30 which is supported at its ends by side frames 32 on opposite sides of the pulley 22. The outer belt 26 is guided and maintained under tension by a tension pulley 34 which is spaced from the guide pulley 28 and is journaled on a shaft 36, the 90 ends of which shaft extend through a yoke 38 that is pivoted at its lower end on a stud 40 at the base of the machine. The pulley 34 is urged outwardly to maintain the belt 26 under tension by coiled springs 42 which 95 act through rods 44. The rods 44 are secured at their outer ends to blocks 46 fixed to opposite ends of the shaft 36 and the inner ends of the rods extend through and are guided by blocks 50 pivoted upon pins 52 projecting from the standards 12 and the side frames 32. The springs 42 are coiled about sleeves 54 on the rods 44 and are interposed between collars 56 at the outer ends

100

- of the sleeves and the pivoted blocks 50. The springs 42 are adapted to be adjusted to vary the tension on the pulley 34 by means of nuts 58 threaded on the rods which bear against the outer sides of the collars 56. The tension pulley 34 and the guide pulley 28 are so constructed and arranged that the lower stretch 60 of the outer belt is substantially in a horizontal plane and the lower stretch of the belt 24 is at a slight angle thereto, which arrangement of the lower stretches of the belts forms a feed opening through which the articles may be presented to the press. This permits the 10 blocks of lifts or other articles to be continuously fed to or placed upon the lower stretch of the belt 26 and as they are being fed thereby to the pulley 22, the lower stretches of the two belts cooperate to apply a gradually increasing pressure thereto. The outer belt 26 is sufficiently flexible so that as a plurality of articles are fed about the pulley 22, the belts and pulley cooperate to apply a uniform pressure thereto even 15 though the articles vary in height. The pulley 22 is of such diameter and is driven at such speed that when the articles reach the upper stretches of the belts, the paste which secures the layers together is properly set. The upper stretches of the belts are so arranged as to form discharge openings through which the articles that have been acted upon by the press are allowed to drop by gravity into a suitable chute 62 20 which conducts them from the press. This chute is secured by bolts 64 to the ends of the side frames 32. Means are provided for removing the articles from the upper stretches of the belts and conducting them into the chute in case the blocks should adhere to the surfaces of the belts. Such means comprise strippers 65 and 66 that are pivoted at 68 on the chute 62 and are respectively pressed toward the belts by means 25 of coiled springs 70.
- The nature and scope of the invention having been indicated, and a mechanism embodying the several features of the invention having been specifically described, 30 what is claimed is:—
1. A press having, in combination, two opposed members of flexible sheet material, and means for actuating said members to apply pressure uniformly to a plurality of articles of varying height placed between said members while maintaining the articles substantially flat.
  2. A press having, in combination, two opposed strips of flexible material, means 35 for moving said strips in unison in the direction of their length, and means for causing said strips during the movement thereof to apply pressure to an article placed between them while maintaining the article substantially flat.
  3. A press having, in combination, two travelling belts arranged one within the other having portions thereof in superposed relation, and means for tensioning one of said belts to apply pressure to an article placed between said superposed portions.
  4. A press having, in combination, two travelling belts having portions thereof in superposed relation, and a tension pulley engaging one of said belts to apply pressure to an article placed between said superposed portions while maintaining the article substantially flat.
  5. A press having, in combination, a pulley, and means including a belt having a substantially horizontal stretch cooperating therewith to feed an article between the pulley and the belt and about the pulley and simultaneously apply pressure to the article while maintaining the article substantially flat.
  6. A press having, in combination, a relatively large pulley, a belt extending about the pulley, a guide pulley for the belt, said pulleys and belt all lying in the same plane, means for driving the belt and pulleys, and means cooperating with the belt and pulleys to apply pressure to an article interposed between the belt and large pulley, said pulleys so constructed and arranged as to form a substantially horizontal feed opening between one stretch of the belt and the pulley and a discharge opening between the other stretch of the belt and the pulley.
  7. A press having, in combination, a relatively large pulley, a belt extending about the pulley, a guide pulley therefor, means for driving the belt and pulleys, a second belt having a portion thereof overlying the portion of the first belt in engagement with the large pulley, and a tension pulley for the second belt, said pulleys being so constructed and relatively arranged as to provide a feed opening between stretches of the belts through which an article may be presented to said overlying portions of the belts and to provide a discharge opening between stretches of the belts through which an article may be discharged from said overlying portions of the belts.
  8. A press having, in combination, a pulley, a belt having a substantially horizontal stretch for feeding an article to the pulley, and means cooperating with the belt and pulley to apply pressure to the article while maintaining the article substantially flat.
  9. A press having, in combination, a pulley, a pair of belts arranged one within the other for applying pressure to an article interposed between them and for feeding the article under pressure about the pulley, and means for conducting the article away from the belts after being acted upon thereby.
  10. A press having, in combination, a relatively large pulley having a horizontal

- axis, two belts extending about the pulley in superposed relation, means for driving the belts and pulley, and guide pulleys for the belts, said pulleys so relatively arranged 5 that one of the stretches of the outer belt is positioned in a substantially horizontal plane to permit an article to be placed thereon and fed to the large pulley and a stretch of the inner belt is so positioned relatively 10 to said stretch of the outer belt that the belts cooperate to apply a gradually increasing pressure to the article as it is fed thereby to the large pulley.
11. A press having, in combination, a 15 relatively large pulley having a horizontal axis, two belts extending about the pulley in superposed relation, means for driving the belts and pulley, guide pulleys for the belts, said large pulley and the guide pulley for 20 the outer belt so relatively arranged that one of the stretches of the outer belt is positioned in a substantially horizontal plane to permit an article to be placed thereon and fed to the bottom of the large pulley where- 25 upon the belts cooperate to feed the article about the pulley, and stripping devices for stripping the article from the belts after it is fed about the large pulley.
12. A press having, in combination, a 30 relatively large pulley having a horizontal axis, two belts extending about the pulley in superposed relation, means for driving the belts and pulley, guide pulleys for the belts, said pulleys so relatively arranged that an 35 article may be placed on one of the belts and fed to the large pulley whereupon the belts cooperate to apply pressure to the article and feed it about the large pulley, and means for conducting the article trans- 40 versely of the belts after it is fed about the large pulley.
13. A press having, in combination, a 45 relatively large pulley having a horizontal axis, two belts extending about the pulley in superposed relation, means for driving the pulley and belts, a guide pulley for the inner belt, a guide pulley for the outer belt, a spring acting through the guide pulley for the outer belt to tension the outer belt, said 50 pulleys so arranged that a stretch of one of the belts is positioned in a plane to permit an article to be placed thereon and fed thereby to the pulley whereupon the belts cooperate to feed the article about the pulley 55 and apply pressure thereto, and means comprising stripping devices and a chute for conducting the article transversely of the belts after it is fed about the pulley.
14. A heel press having, in combination, 60 a rotatable pulley, means including a flexible, flat belt having a substantially horizontal stretch, extending about said pulley to receive and feed heels to a position between the belt and the pulley for simultaneous 65 traverse around the pulley, means for applying a yielding tension to said belt, whereby heels of varying heights will receive uniform pressure, and a supporting frame constructed to permit free access to said horizontal stretch. 70
15. A heel press having, in combination, a frame supporting a fixed rotatable pulley and a movable rotatable pulley of smaller diameter, in alinement on parallel shafts; a flexible, flat belt extending about 75 said pulleys forming feed and discharge openings, for the heels to be pressed, between the belt and the fixed pulley, said pulley having a circumference many times the length of the heel enabling it to hold a large 80 number of heels under pressure simultaneously; and means connected between the frame and movable pulley for applying a yielding tension to the belt providing uniform pressure on heels of different heights 85 held between the belt and fixed pulley.
16. A press having, in combination, two rotatable pulleys mounted a distance apart and in alinement, one pulley being of relatively large diameter compared to the other 90 and supported on a shaft having fixed bearings in the frame, the small pulley being supported on a parallel shaft in a bearing pivotally mounted in the frame; an open belt extending about said pulleys forming two 95 straight stretches; springs applied to the pivotal bearing of the small pulley for exerting a yielding tension on the belt whereby articles fed between the belt and pulley on one straight stretch will be pressed there- 100 between by pressure from said springs and will be discharged on the other straight stretch, and means for directing the pressed articles out of the press.
17. A press having, in combination, a relatively large pulley and two smaller pulleys all in alinement, said small pulleys being both on the same side of the large pulley, a belt extending about the large pulley and the small pulley nearest thereto, and a 110 second belt extending about the large pulley and the other small pulley outside the first named belt, the relative arrangement of the bearings of said pulleys being such that angular feed and discharge openings are 115 formed between the belts for articles to be pressed therebetween by passing around the large pulley.
18. A press having, in combination, a relatively large pulley and two smaller pulleys 120 all in alinement, said small pulleys being both on the same side of the large pulley, a belt extending about the large pulley and the small pulley nearest thereto, a second belt extending about the large pulley and the 125 other small pulley outside the first named belt, the relative arrangement of the bearings of said pulleys being such that angular

feed and discharge openings are formed between the belts for articles to be pressed therebetween by passing around the large pulley, and means for applying a yielding tension to said outer belt.

19. A machine for pressing pasted heels having, in combination, a relatively large pulley, a smaller pulley in alinement therewith, an open belt extending about said pulleys, said pulleys and belt providing a feed opening between one straight stretch of the belt and the larger pulley on which heels may be placed and fed between said belt and pulley, and means adjacent the other straight stretch of the belt for detaching the pressed heels from the press should they adhere

thereto after having been carried about the large pulley.

20. A machine for pressing pasted heels having, in combination, a relatively large pulley, a smaller pulley in alinement therewith, an open belt extending about said pulleys, said pulleys and belt providing a feed opening between one straight stretch of the belt and the larger pulley on which heels may be placed and fed between said belt and pulley, and strippers at the discharge side of the large pulley constructed and arranged to engage and detach the heel should paste at either face thereof cause it to adhere to the press.

ERASTUS E. WINKLEY.
